MANUFACTURE OF UNCHILLED METALLIC CASTINGS BY THE CENTRIFUGAL CASTING PROCESS

William Ridley, Beeston, Nottingham, and Percy Hutchinson Wilson, Nottingham, England

Application November 27, 1935, Serial No. 51,926
In Great Britain December 24, 1934

10 Claims. (Cl. 22—88)

This invention relates to the manufacture of metallic castings such for instance as pipes by centrifugal casting processes in which use is made of dry pulverulent materials which are introduced 5 into the rotating mould prior to and preferably closely in advance of the introduction of the molten metal, so as to produce a film or lining on the interior surface of the revolving mould for the essential purpose of preventing the chilling 10 of the casting. Various powdered materials have been employed to that end and satisfactory results have been obtained by the use of ferro-silicon or aluminium or a substance including aluminium in metallic form.

15 Various methods also for introducing the powdered material into the mould have been devised, a common practice residing in the use either of a suitable container in the form of a shallow trough charged with a quantity of the powdered material and adapted to be tipped 20 within the mould, or of a container of a tubular kind through or along which the powdered material is discharged so as to form a film on the interior of the mould just prior to casting. Efforts have been made to create such a film or 25 lining within the mould also by blowing the powdered material against the mould interior with the aid of compressed air, or by feeding it into the mould by way of tube means.

30 In contradistinction to the known methods the principle involved according to the present invention resides in the use of a reciprocating carrier or propulsion tube or conduit moving, according to a preferred arrangement, inside an 35 outer sleeve or casing, forward movement or discharge of the material being effected by arresting the forward stroke of the carrier tube as by a sudden stoppage of a uniformly accelerated feed stroke thereof followed by a quick withdrawal or rapid initial acceleration of the carrier 40 tube on its return stroke with a view to effecting propulsion of the powdered material by a combination of jarring and quick withdrawal of the carrier tube from under the material at the forward end of the stroke while properly controlling these movements between the ends of the respective strokes.

45 The reciprocating action of the carrier tube or the like may be obtained mechanically, for example by means or under the control of an appropriately designed cam gear or electromagnetically such as by means of an electromagnet of a convenient type.

50 The invention also consists in methods and apparatus as set out more particularly in the

appended claims, including in particular the method of feeding finely divided material into a region of a rotary mould relatively remote from the supply, which consists in discharging said material from said supply on to a surface extendible to such region and imparting to said surface and material thereon a longitudinal forward movement towards said region, arresting said movement suddenly and rapidly accelerating said surface in reverse direction for withdrawing it from under material moved forwards therewith in the preceding stroke, repeating said forward and reverse movements at a relatively high frequency to effect a desired rate of feeding. It also includes apparatus for use with centrifugal casting machines, comprising a member constituting a conduit of elongated form adapted to be inserted into a rotary mould, means for depositing finely divided mould-coating material in one end of said member, and means for subjecting the latter to longitudinal reciprocatory or vibratory movement including a sharp determination of that stroke of said movement which is directed to the opposite end of said member and rapid initial acceleration during the following stroke.

55 Referring now to the accompanying drawings:—

Figures 1 and 1a are complementary longitudinal sectional views of a centrifugal mould apparatus incorporating one form of the present invention;

Figure 2 is a fragmental cross-section of the metal-charging trough and associated powder supply conduit included in Figure 1;

Figure 3 is a side elevation of a form of powder supply actuating mechanism alternative to that included in Figure 1;

Figures 4 and 5 are side elevation and plan views respectively of a preferred construction of 40 the type of powder supply actuating device shown in Figure 1.

55 Referring now to the drawings, which show one convenient construction of apparatus in which the invention may be carried into effect, and ignoring at first the specific means used for producing the aforementioned reciprocatory or vibratory action, the reciprocating or carrier tube *a* is arranged for protection inside an outer sleeve or tube *b* the latter being stationary and placed 50 preferably under the lining blocks *c* forming part of the usual metal runner or casting trough *d* of the centrifugal casting machine which is retractable in relation to the mould. The inner or carrier tube *a* projects at the delivery region *e*

beyond the outer tube *b* and is with advantage peripherally perforated at *a*₁ to allow the dry powdered material to fall through and distribute itself uniformly in the form of a relatively wide ribbon on the surface *f* of the mould at a suitable distance in advance of the deposition of the molten metal which takes place over the end *d*₁ of the runner trough. At its other end this inner or carrier tube is connected as by a bend *g* or a branch or T-piece *g*₁ to a suitable receptacle *h* containing the dry powdered material, such for instance as ferro-silicon. This receptacle can be either, as shown, stationary and connected to the carrier tube by means of a flexible pipe *j* or can be arranged to move with the tube.

For the electromagnetic actuation of the carrier tube *a* the devices referred to can be either of the plunger solenoid type (see Figure 3) for direct current operation, or alternatively a contactor type of magnet for alternating current as embodied in Figure 1. Each magnet will be operated at the required frequency which will depend upon the nature, state of subdivision, fluidity of the material and other factors, including the rate of delivery required. In the D. C. type of actuator, current is supplied through an interrupter or distributor to a coil *m* surrounded by a pole limb. This coil, when energized, attracts an armature in the form of a plunger *n* passing through the centre of the coil, the plunger being suitably connected as by way of the branch piece or T *g*₁ to the carrier or propulsion tube *a* which delivers the material to the end of the casting trough.

The plunger or armature *n* as shown in Figure 3 is provided with an adjustable dashpot indicated by *n*₁, air, liquid or friction being the medium, to provide suitable retardation of the return stroke and uniform acceleration of the forward stroke, the object being to obviate slipping of the material under its own inertia in the tube at the commencement of the forward movement and the completion of the return movement.

In the case of D. C. supply, the latter would be provided from mains at any voltage to a distributor or interrupter arranged to provide current at the required frequency or periodicity. One distributor capable of supplying current to any number of machines could be used.

In the case when an A. C. supply is to be used, and referring to Figure 1, current at any suitable periodicity may be supplied direct to the coil *m*₁ surrounding a pole limb, which in turn attracts an armature *n* coupled by suitable means, e. g. through a sort of parallel motion linkage system *o*, *o*₁, to the carrier or propulsion tube *a*. Slow stopping and starting of the return and forward stroke respectively is obtained by incorporation of suitable dashpot means similar to that embodied in the D. C. equipment, or alternatively and as actually shown, by means of an auxiliary spring inserted as at *s*₁ in lever part *o* of the coupling between the armature and the propulsion tube. This spring would be strong enough to overcome the static friction of the tube, but would be compressed to a limited extent in overcoming the inertia of same. Such an arrangement provides a gradual slowing down of the tube on the return stroke, and a gradual speeding up of same on the forward stroke, while at the same time permitting sharp metal to metal contact at the end of the forward stroke, and thereby providing the necessary jarring action

to the material and consequent propulsion thereof and discharge from the tube.

In the construction shown in Figures 4 and 5, an armature element *n* vibrated by the action of the coil *m*₁ is attached at one end by a pivot *n*₂ to the magnet body and also pivotally to a bridge member *n*₃, one end of which is secured as shown to the bend *g*₁ and thereby to the propulsion tube *a*. The member *n*₃ which embraces the magnet is attached at its opposite end to guide means *n*₄ adjustable within a support *n*₅, and is operatively connected also at each end to leaf springs *n*₆ in such a way that the entire bridge member and positively connected parts may reciprocate or vibrate with the armature element *n* against the resilient action of the springs, to an extent regulatable by the adjustment nut devices at *n*₇ collectively; and conveniently indicated by a pointer *n*₈ and dial *n*₉. The impact of metal to metal above mentioned occurs, as most clearly seen in Figure 4, at the nut and/or washer faces at *n*₁₀, which are separated axially when the tube *a* is retracted by the magnet armature but which would otherwise bear together under the action of the springs *n*₆.

Control of the amount of material propelled may be effected by varying the gap of the magnet as by a handwheel and consequently the stroke of the tube, this variation being suitably registered on a dial; or alternatively by inserting a potentiometer in series with the coil so as to vary the voltage energizing the same, thereby varying the strength of the magnetic pull. By this means remote control of the apparatus is readily effected.

In practice this form of apparatus has been found to be more positive in its action than any other form known at present, and to ensure reliable application of a more uniform film of powdered material in the mould and in the correct relation to the point of the metal deposition therein.

Having now described our invention, what we claim as new and desire to secure by Letters Patent is:—

1. Apparatus for feeding finely divided powder over the interior of a rotary mould, comprising a member entrable into and relatively longitudinally movable in said mould, a powder supply container attached to said member, means generally movable with said member and providing a surface extendible from said container into said mould, said means being reciprocable in relation to said member, means for discharging said powder from said container on to said surface, driving means for reciprocating said reciprocable means in relation to said member and means governing the action of said driving means for arresting suddenly the forward stroke towards the mould interior and producing acceleration during the reverse stroke thereby withdrawing said surface from under powder moved forward therewith in said forward stroke, said driving means being operable at a relatively high frequency to effect feeding at a desired rate.

2. Apparatus according to claim 1, in which said driving means produces a uniformly accelerated forward stroke of said reciprocable means and said governing means includes stop means operative to sharply arrest said forward stroke and spring means operative to effect rapid initial acceleration in the reverse stroke, thereby effecting general forward propulsion of the material along said surface by a succession of jarring and quick withdrawal of the supporting surface from under the material.

3. Apparatus for use with centrifugal casting machines, comprising a metal-charging trough, a member constituting a conduit of elongated form adapted to be inserted with said trough into a rotary mould, means for depositing finely divided mould-coating material in one end of said member and means for subjecting the latter to longitudinal reciprocatory or vibratory movement in relation to said trough, said movement including a sharp termination of that stroke thereof which is directed to the opposite end of said member and a rapid initial acceleration during the following stroke.

4. In centrifugal casting apparatus a rotary mould, an external supply for finely divided material, a conduit for conveying said material from said external supply into the mould interior, means axially advanceable and retractable in relation to said mould said means forming a support for said conduit for the general movement thereof into and out of the mould, means enabling the conduit to be reciprocated longitudinally in relation to said support-forming means, and means for reciprocating said conduit for propulsion of said material along the same into the mould.

5. Apparatus according to claim 4 wherein said support-forming means consists of a runner trough for the introduction of metal to be cast said conduit being of tubular form reciprocatable within guiding means carried by said trough, and terminating in a powder-discharging end not greatly removed from the metal-discharging end of said trough.

35 6. Apparatus according to claim 4 wherein said support-forming means consists of a runner trough for the introduction of metal to be cast, said conduit consisting of a tube reciprocatable

within an outer guide tube fixed in relation to and insertable into the mould with said trough, said tube being connected at one end to said supply and extending through said guide tube to protrude in a discharging end not greatly removed from the discharge end of said trough. 5

7. Apparatus in accordance with claim 4, in which said reciprocation means comprises an electro-mechanical vibrator device operative between said conduit and said support therefor. 10

8. Apparatus according to claim 4, in which said reciprocation means comprises an electro-magnetic vibrator device operatively coupled to said conduit and the support therefor through means introducing dissimilarity in the strokes 15 constituting a vibration.

9. Apparatus according to claim 4, in which said reciprocation means comprises an electro-magnetic vibrator device operatively coupled to said conduit and the support therefor through means 20 introducing an abrupt termination to that stroke of a vibration in the direction from the supply towards the mould, and uniform acceleration and retardation during the remainder of such vibration. 25

10. Apparatus according to claim 4, in which said reciprocation means comprises an electro-magnetic vibrator device operatively coupled to said conduit and the support therefor through means comprising resilient means imparting uniformity of acceleration and retardation to the vibrations generated by said reciprocation means, and means determining one stroke of a vibration in a sudden shock by impact of metal surfaces. 30 35
